UNITED STATES PATENT OFFICE.

EDWARD LELAND BASS, OF CHICAGO, ILLINOIS.

TEE-FORMING DEVICE.

Application filed March 5, 1927. Serial No. 172,945.

This invention relates to devices for forming tees for use in playing golf, and more particularly to a device of this general character including a mold or cup open at its lower end and a plunger movable in the upper end of the mold body for expelling the tee form.

Devices of this general character are known, but such devices are open to several objections. As a rule, they occupy appreciable space and are rather cumbersome to carry in the pocket. A further objection to the present devices of this character in use is that the plunger is not held sufficiently snugly to prevent looseness or play thereof, rendering it very difficult to accurately form the tee, and particularly difficult to form a depression centrally of the top of the tee for reception of the ball. A further objection to devices of this general character now in use is that the spring and the movable parts associated with the plunger are not properly housed and enclosed to protect the same from the injurious effects of the sand. So far as I am aware, in all devices of this type now in use it is possible to produce a tee of but one height from a given device. This is very objectionable as, under certain conditions, a low tee is found desirable whereas, under other conditions, a higher tee is desirable. It is also true that some players consistently use a low tee, whereas other players consistently use a relatively high tee. With the tee forming devices at present in use these varying conditions cannot be met, and such devices are, therefore, not entirely satisfactory. In addition to the objections above outlined, it is one of the primary objects of my invention to provide a tee forming device of simple and inexpensive construction by means of which tees of different heights can be readily formed. Further objects and advantages of my invention will appear from the detail description.

In the drawings:

Figure 1 is an elevation of a tee forming device constructed in accordance with my invention;

Fig. 2 is a section taken substantially on line 2-2 of Fig. 1;

Fig. 3 is a fragmentary section on an enlarged scale taken substantially on line 3-3 of Fig. 2;

Fig. 4 is a plan view of the lower section 55 of the body; and

Fig. 5 is a fragmentary inner face view of

the lower portion of the upper section of the body.

The device includes a frusto-conical body formed of an upper section 1 and a lower section or extension member 2. This body is open at its lower end and is provided at its upper end with a relatively thick top wall 3 from which extends a comparatively wide peripheral flange 4 inclined upwardly and outwardly of the body. A neck 5 extends upwardly from the central portion of wall 3 and this wall is provided in its upper face with a depression or recess 6 forming a continuation of the bore of the neck. A plunger rod 7 is slidably mounted through the top wall 3 within neck 5 and concentric therewith. A hollow cylindrical head 8 fits snugly within neck 5 for sliding movement therein, the rod 7 having its upper end secured in the top 9 of the head. The neck and the head form a housing for an expansion coil spring 10 mounted about the rod and seating in the head and in recess 6, this spring being completely enclosed and protected by the head and the neck. A plunger 11 is secured on the lower end of rod 7, this plunger being provided with a central bore extending from its upper face and internally threaded for reception of the threaded lower end of the rod. The lower face 11^a of the plunger is of frusto-spherical shape and is curved on a radius approximately equal to the radius of a standard golf ball. The peripheral edge 11^b of this plunger is inclined to correspond with the inclination of the inner face of the body, and the plunger is of such diameter that this peripheral face 11^b contacts with the inner face of the body a short distance below the upper end thereof to limit upward movement of the plunger. This provides a tight closure about the plunger which serves to prevent entry of sand or other gritty substances into the spring housing about the rod 7. It will be noted that the body portion of head 8 is of greater diameter than the rod 7 and the area of contact between the head and neck 5 is relatively large so as to guide rod 7 and consequently plunger 11 during movement thereof, preventing undue looseness or play of the plunger. This is of material assistance in forming the tee and in positioning the recess for reception of the ball accurately in the upper end of the tee.

Upper section 1 of the body is rabbeted at

its lower end and from its inner face, at 12, forming a depending peripheral flange 13. The rabbet 12 is adapted for reception of a flange 14 formed at the upper end of the 5 lower section or extension member 2, this member being rabbeted from its outer face at 15. The flanges and the rabbets of the sections 1 and 2 are so related and proportioned as to fit snugly one within the other 10 and have sufficient frictional contact to, under normal conditions, hold the sections snugly together. With the sections in operative relation the inner face of section or extension member 2 forms a continuation of 15 the inner face of section 1, the inner faces of these two sections being flush to avoid objectionable projections which would interfere with proper forming and depositing of the tee. To eliminate any possibility of the 20 lower section or extension member 2 being detached when not desired, I provide the slots 15 in the inner face of flange 13, the lower wall 15^b of the upper arm 15^a of the slots being inclined upwardly from their 25 outer ends, as illustrated in Figure 5. Pins 16 are secured in flange 14 of extension member 2 for cooperation with the slots. In applying the extension member the pins are inserted through the vertical arms of the 30 slots and the extension member 2 is then turned in a clockwise direction, the contact of the pins with walls 15^b serving to draw the extension member onto the section 1 so that the flanges 13 and 14 fit snugly within 35 the rabbets 15 and 12, respectively, with their outer edges in abutting relation with the inner end walls of the rabbets. This provides a snug closure between the two sections of the body, which serves to effectually 40 prevent the entry of sand or other gritty substances therebetween. When the lower section or extension member 2 is applied to the upper section 1, the device is adapted for 45 forming high tees. The moistened sand is packed firmly into the body either by pressing the device into the sand or by pressing the sand into the body with the hand, as preferred. The device, with the sand packed 50 therein, is then positioned closely adjacent the surface on which the tee is to be deposited, and plunger 11 is depressed by engaging the fingers beneath flange 4 and pressing downwardly on head 8 with the thumb. The tee formed is thus ejected and 55 the rounded frusto-spherical face 11^a of the plunger 11 provides a rounded depression in the top of the tee for reception of the ball.

By detaching the extension member 2, the device is adapted for forming low tees. It will thus be seen that the device can be used 60 for forming tees of two heights, the heights selected being those most commonly used by golf players.

By recessing the head for reception of the end of the spring, and providing the hollow head 8 which receives the upper end of the spring 7, the spring is completely enclosed and housed so as to be protected from sand or other gritty substances, and the device as a whole is of neat, inexpensive, and compact 70 construction and can be readily carried in the pocket.

What I claim is:—

1. In a golf tee mold, an upper body section open at its lower end, an extension member secured to the lower end of the body section and having its inner face flush with the inner face of said section, and means for releasably securing the extension member to the body section. 75

2. In a golf tee mold, an upper body section open at its lower end and rabbeted from its inner face forming a depending peripheral flange, an extension member rabbeted from its outer face and at its upper end forming a peripheral flange at the upper end of said member, the flanges of the body section and extension member fitting snugly into the rabbets of the extension and the body section, respectively, and means for detachably securing the extension to the body section. 85

3. In a golf tee mold, an upper body section open at its lower end and of a depth to form a tee of average height, and an extension member detachably secured to the upper body section and forming a continuation thereof for producing a tee of greater than average height. 95

4. In a golf tee mold, an upper body section open at its lower end and of a depth to form a tee of average height, said section having a groove in its inner face and extending from its lower end, and an extension member having an element projecting into said groove and detachably secured therein, the extension member constituting a continuation of the body member and coacting therewith to form a tee of greater than average height. 100

In witness whereof, I hereunto subscribe my name this 3rd day of March, 1927.

EDWARD LELAND BASS.
